Dec. 306

John S. Rathbone of Albany N.Y.
Letters Patent No. 306. Dated August 13. 1850.

The Schedule referred to in these Letters Patent and making part of the same.

To whom it may concern:

Be it known that I John S. Rathbone of the City of Albany and State of New York, have produced a new ornamental Design for a Coal Cylinder Stove and I do hereby declare that the annexed and accompanying drawings are full and accurate delineations of the ornamented parts of said Stove, with their several ornaments, the back & side plates not shewn in the drawings being similar to and symmetrical with the front and side plates shewn, and where portions of the plates are shewn, the portions not shewn with their ornaments being similar to, & similarly & symmetrically ornamented with the portions shewn.

What I claim as my production and desire to secure by Letters Patent is the combination & arrangement of Ornamental figures & forms represented in the accompanying drawings, forming together an ornamental design for a Coal Cylinder Stove.
